CALLING MECHANISM FOR TELEPHONE-EXCHANGES.

1,327,622.

Specification of Letters Patent. Patented Jan. 13, 1920.

Application filed March 11, 1918. Serial No. 221,598.

To all whom it may concern:

Be it known that I, FRANK A. LUNDQUIST, a citizen of the United States of America, and a resident of the city of Chicago, county of Cook, and State of Illinois, have invented certain new and useful Improvements in Calling Mechanisms for Telephone-Exchanges, of which the following is a specification.

10 My invention relates to calling mechanisms for use in automatic telephone exchanges and has for its object the construction of a device which an operator may use continuously and rapidly and which will 15 cause a minimum of inconvenience to such operator.

20 The accompanying drawings show the mechanism with inclosing case and some connections omitted as not being necessary to an understanding of the invention. Also, the mechanism is shown in part in diagram where a diagrammatic showing is easier to describe than a full detail of actual construction. In the said drawings.

25 Figure 1 is a side elevation of the mechanism with some of the keys depressed preparatory to sending calling impulses;

Fig. 2 is an end view in the direction 2 of Fig. 1, some parts being omitted;

30 Fig. 3 is a section on line 3—3 of Fig. 1, but with all of the keys in elevated position;

Fig. 4 is a horizontal section on line 4—4 of Fig. 1;

Fig. 5 is a plan with some parts broken away with some of the parts below in section;

Fig. 6 is a section on line 6—6 of Fig. 1;

Fig. 7 is an enlarged vertical section through the valve chest; and

40 Fig. 8, 9 and 10 are details.

The upper face of the calling mechanism has on it a plurality of rows of keys, the keys in each row being numbered from "1" to "0" inclusive, as shown in Fig. 5. In Figs. 45 drawings, four rows of keys are shown, and a device having four rows of keys is adapted to call any number up to "9999." In Figs. 1 and 2, one key in each row is shown depressed. These keys are indicated in Fig. 5 by an extra dark border placed on this drawing for the purpose of identification. With these keys depressed the device is set for calling station number "4567." In addition to the numbered keys there is a "start" key 50 which will be described later.

The mechanism is located between a lower plate 11 and an upper plate 12. Supported on posts 13 (Fig. 1) is an extra plate 14. The numbered keys are mounted on the upper ends of stems 15 guided in plates 12 and 14, and are normally supported in an elevated position by springs 16.

On the plate 12 are ears or lugs 17, and pivoted to these lugs are swinging links 18. Supported on the lower ends of these links 65 are plates 19, there being one plate 19 extending longitudinally under each row of keys, and each plate 19 having therein a series of slotted holes for the stems 15 of its row. Springs 20 (Fig. 1) normally hold 70 these plates 19 to the left. On the stems 15 are lateral projections 21. When a plate 19 is to the left, the edges of the slotted holes come under the projection 21 and locks the keys against depression. Also, if a 75 plate 19 is moved to the left after one of the keys in its row has been depressed, then the edge of the slotted hole will come over the projection 21 on the depressed key and hold it in its depressed position. The swinging 80 plates 19 are locking plates to hold keys in either elevated or depressed position when said plates are to the left, but said plates leave the keys free to move when said plates are moved to the right.

85 Supported between plates 11 and 12 at opposite ends of the device are spindles 22 and 23 which carry sprocket wheels 24 and 25, and mounted on these sprocket wheels are belts or tapes 26. There is one tape 26 90 for each row of keys, and each tape has thereon a stop 27. On spindles 22 and adjacent posts 28 are springs 29 which act to rotate said spindles, and hence to move the tapes, in a direction which will bring the 95 stops 27 against the left hand side of pins 30 depending from the right hand ends of locking plates 19. The springs 29 are strong enough to overcome the springs 20 with the result that the normal position 100 of lock plates 19 is the unlocked position which permits the numbered keys to be freely moved up or down.

105 Located under each row of key stems 15 is a long bar 31 supported on links 33 and 34. The links 33 are secured rigidly to a shaft 35, while the links 34 are loose on pins or studs. The bar 31 with its links forms a "parallel" motion so that when a bar is depressed by a descending key stem it will 110

remain under such stem. At one end the shafts 35 and adjacent pins are supported in brackets 36, while at the other end they are shown as supported on the side of the 5 air chest 46 to be later described.

The link 34 at the right is made laterally 10 slideable on its pin 37, but is normally held in the position shown by a spring 38 on a part of the bar 31. On the pin 37 is an arm 15 39, one part of which projects laterally under the adjacent link 34, and a spring 40 on said pin acts to elevate said arm and link, and consequently the bar 31. It is to be understood that these parts are duplicated 20 for each row of keys on the machine.

Located in the lower part of the machine, 25 and associated with each tape 26, is an air cylinder 41 having a piston 42, and secured to each piston is a rack 43 adapted to engage a gear 44 on a spindle 22. The cylinder 30 is closed by a head on the side of the piston opposite the rack, and from this head there is a pipe 45 extending to an air chest 46. Compressed air is conveyed to this chest, from any suitable supply, by a pipe 47 (Fig. 4), and is represented in Fig. 7 by the conduit 48 which runs longitudinally through the chest 46. From this conduit there is a branch 49 leading to the pipe 45, 35 and another branch 50 for exhaust.

The pin 37, previously described as the support for the link 34, is, in fact, the outer 40 end of a valve for controlling the supply of air to the corresponding cylinder 41. The inner end plugs the connection between the 45 conduit 48 and the branch 49, and has in it a transverse hole which matches branch 50 when the connection is closed between 48 and 49. The arm 39 is secured to the pin 37, and when said arm is depressed as a result 50 of depressing one of the numbered keys on the machine, the valve is turned to open the connection between 48 and 49, and to close the exhaust 55 50. A screw 51 serves as a means for adjusting the exhaust opening so that the rate of exhaust may be anything desired.

The sprocket wheels 24 on spindles 22 have long teeth 52, and in the paths of 55 these teeth are levers 53 pivoted at 54. Springs 55 normally hold the ends of levers 53 against projections 56 on slide 57 operating in a guide 58 on plate 12. When a rack 43 operating on its gear 44 moves a sprocket 60 wheel 24 in the direction of the arrows shown in Figs. 4 and 5, the teeth 52 strike a lever 53 to move it away from the adjacent projection 56. This action does not affect the position of the slide 57. But when 65 a sprocket wheel moves in the opposite direction, the teeth 52 strike the lever 54 on the sprocket side and cause a movement of the slide 56. On one end of this slide is a piece of insulation 59 which rests against a contact spring 60. When the slide 58 is moved

as described it pushes the spring 60 away from its companion contact spring 61 and acts to break an electric circuit indicated by the wires shown extending from springs 60 and 61. The spring 60 is made stiff enough 70 to return the slide 57 to its normal position after having been moved by a vibration of a lever 53.

At the other end of the keyboard is shown a "start" key 62, on the lower end of the 75 stem of which is a cam 63. (Fig. 1.) Pivoted at 64 on a bracket secured to plate 11 is a long and laterally flexible lever 65 having a pin 66 on its upper end, which pin is engaged by the cam 63 to move the lever 80 65 on its pivot 64 when the start key 62 is depressed. When the start key has reached its lowest position the pin 66 catches over the cam 63 to hold the start key in its depressed position until released as herein-after described. That part of lever 65 which is located on the opposite side of the pivot 64 is marked 67 and engages the side of the adjacent link 34 when said link is in its lower position. When the descending cam 90 63 engages pin 66 to move lever 65, the arm 67 of said lever pushes link 34 from the catch on arm 39, whereupon spring 40 raises said arm 39 to turn pin 37 and thus close the air connection between 48 and 49, and at the 95 same time to open the exhaust 50.

Pivoted at 67 (Fig. 4) on the bottom of the air chest 46 is a lever 68, one end of which is connected by a link 70 with the pin 30 depending from that lock plate 19 100 which is on the same side of the machine as the start key. The other end of the lever 68 has a projection 71 engaging the next link 34 and adapted to push it from engagement with the adjacent arm 39 when the 105 lever 68 is moved on its pivot 67. Similarly there are other connections of the same kind between the next pin 30 and the next link 34, and the same thing is repeated until the last link 34 is reached.

Pivoted at 72 (Fig. 4) on a convenient part of the frame work is a bell crank lever 73, one arm of which is adjacent to the last pin 30. The other arm of the bell crank lever 73 has connected thereto a link 74 115 which extends across the machine and contacts the side of the flexible lever 65. When the bell crank lever 73 is moved on its pivot, as will be described, the link 74 pushes the lever 65 to one side so that the pin 66 is 120 released from cam 63, whereupon the start key 62 will rise under the action of the spring on its stem.

In operating the device the operator will 125 depress those keys on the keyboard which will indicate the number to be called. It is here assumed that the number "4567" is to be called, and the keys for that number are indicated by dark borders in Fig. 5. Upon depressing key number "4" in the thousands 130

column of the keyboard, the corresponding bar 31 will be moved downward on its links 33 and 34. As the corresponding arm 39 on pin 37 is at this time in engagement with 5 the adjacent link 34, this downward movement of bar 31 results in turning the pin 37 to open the connection between the air channel 48 and that passageway 49 which leads to the pipe 45 connected to the correspond- 10 ing air cylinder 41.

The admission of compressed air to the cylinder behind piston 42 drives that piston toward the opposite end of the cylinder 41 and causes the connected rack 43 to turn its 15 gear 44 and consequently the sprocket wheel 24 on the same spindle. This movement of the sprocket wheel moves the tape 26 thereon so as to carry its stop 27 away from the associated pin 30 and permit the spring 20 20 to move the corresponding lock plate 19 to catch and hold the depressed key in depressed position. When the stop 27 on tape 26 engages the projection 21 on the stem of the depressed key the movement of the piston 42 under the action of the compressed air 25 is arrested. The spacing of the teeth 52 on the sprocket wheel 24 is so related to the spacing of the keys on the keyboard that when key No. 4 is depressed four of the 30 teeth 52 will engage and pass the corresponding lever 53. But this movement under the action of the compressed air is one which moves the lever 53 away from the corresponding projections 56 and conse- 35 quently produces no results.

When key No. 5 in the hundreds column of the keyboard is depressed, it moves the corresponding bar 31 downward and results in turning the corresponding pin 37 to admit compressed air to the corresponding air cylinder 41. The consequent movement 40 takes the corresponding stop 27 away from its pin 30 to contact with the projection 21 on depressed key No. 5. In this case, five 45 teeth 52 pass the corresponding lever 53 and set this part of the apparatus for five contact movements in the same way that the previously described parts were set for four contact movements.

50 In the same way, the depression of key No. 6 in the tens column of the keyboard sets the corresponding parts for six contact movements, and the depression of key No. 7 in the units column sets for seven contact 55 movements. In other words, the apparatus is set for any number of contacts in thousands, hundreds, tens or units by depressing a correspondingly numbered key in the desired column.

60 After the number is thus set up on the keyboard, the operator depresses the start key 62 which first moves the lever 65 and is then caught and held by the pin 66 thereon. Upon this movement of the lever 65, the arm 67 thereon pushes the adjacent

link 34 from the catch on arm 39, and permits said arm to rise under the action of spring 40. This movement turns the pin 37 to close the connection between the air supply 48 and the channel 49 leading to the 70 corresponding cylinder 41. The same turning of the pin 37 also opens the exhaust so that the air in the cylinder 41 may flow out through channel 50 past the screw 51. As soon as the air pressure is thus relieved the 75 spring 29 connected to the corresponding sprocket parts back toward normal position at a rate which is determined by the adjustment of the screw 51.

In this backward movement, the teeth 52 80 on sprocket wheel 24 engage the associated lever 53 to cause reciprocations of slide 57. Each movement thus given to the slide 57 pushes contact spring 60 away from contact spring 61 and breaks a circuit in 85 the telephone exchange at this point. As soon as a tooth 52 passes a lever 53, the spring 60 acts to return the slide 57 to normal position and 60 again engages 61. When the stop 27 on the returning tape 26 90 comes to the pin 30 on the lock plate 19, the force of the spring 29 overcomes that of the spring 20 with the result that the lock plate is released from the projection 21 on key No. 4 and said key rises by action of 95 its spring 16. At the same time the movement of the tape is arrested by reason of the fact that the lock plate 19 has only a very short movement by reason of contact between the tape-stop 27 and the pin 30. 100

The spacing of the teeth on the sprocket wheels 24 corresponds to the spacing of the keys on the keyboard. Thus, when a stop 27 moves back from a key No. 4 to contact with its related pin 30, the teeth 52 will give 105 four reciprocations to the slide 57 and cause four successive make and break connections at contact 60-61. When a stop 27 moves back from a key No. 5, there will be five make and break connections at contacts 110 60-61. From key No. 6 there would be six make and break connections, and so on.

The return of the thousands tape 26 causes its stop 27 to move pin 30, and connected to this pin is link 70 on lever 68. 115 The movement of this lever causes its projection 71 to move the next link 34 so as to release it from its catch 39. When this occurs the valve for the hundreds cylinder 41 is opened by its spring 40 with the result that the hundreds tape 26 will return to its normal position and cause its stop 27 to engage the adjacent pin 30 and release the depressed key in the hundreds column of the key board. In this return movement 120 there will be as many reciprocations of the slide 57 as was indicated by the number on the depressed key. The completion of the return of the hundreds tape releases, in the same way, the connections for the tens tape, 130

and the tens tape releases for the units tape. When the stop 27 on the units tape engages its pin 30, (upper right hand portion of Fig. 4), it moves the bell crank 73 to move link or slide 74 so as to push to one side the flexible lever 65 and release pin 66 from the cam 63 on start key 62. When this occurs the start key rises to its normal position under the action of the elevating spring on its stem.

When the key on the key board is depressed as described it moves its bar 31 downward on its links 33 and 34. The links 33 are secured to the shaft 35, and on this shaft is a spring 75 which has one end secured to the shaft and the other end secured to the bracket 36. The depression of the bar 31 winds this spring up, and when the key is later released, the spring acts to return the bar 31 to its normal elevated position. This occurs for each bar 31 after the corresponding arm 39 has been released from its adjacent link 34 and has risen under the action of its spring 40. In the rising of a bar 31 under the action of its spring 75, the link 34 is raised above arm 39, whereupon the spring 38 moves this link 34 laterally to its normal position over the catch on arm 39.

30 What I claim is:

1. In a calling mechanism, a series of keys representing different numbers, a pneumatic device associated with said keys, a source of air pressure for operating the pneumatic device, means by which upon depressing a key having thereon any particular number the pneumatic device will set the mechanism for a number of electrical impulses which correspond to the number on the depressed key, means for releasing the pneumatic device so that the mechanism may return to normal position, and automatically operating means for releasing the depressed key upon the completion of such return movement.

2. In a calling mechanism, a series of keys representing different numbers, a pneumatic device and source of air pressure for operating it, means by which the depression of a key starts the pneumatic device into operation and stops it at a position corresponding to the location of the key depressed, means for releasing the pneumatic device, means for returning the moved parts to normal position when so released, and means operated by the return of the moved parts for making a series of electrical contacts corresponding in number to the number represented by the depressed key.

60 3. In a calling mechanism, a series of keys representing digits in units, a second series of keys representing digits in tens, a pneumatic device for each series, means by which the depression of a key starts

the corresponding pneumatic device into operation and stops it at a position corresponding to the digit represented by the depressed key, means for releasing an operated pneumatic device, means for automatically returning such released device to normal position, and means controlled by one pneumatic device for releasing the next pneumatic device.

4. In a calling mechanism, a key board having a series of keys for units and another series of keys for tens, a power device associated with each series, means by which upon the depression of a key the corresponding power device will be started into operation for a movement corresponding in length to the location of the depressed key, manually operated means for releasing the parts operated by one of the power devices, a spring for returning the moved parts to normal position, and means operated by the return of the parts moved by one power device for automatically releasing the parts operated by the other power device.

5. In a calling mechanism, a contact making device, independent power devices for units, tens and hundreds, a series of keys each for units, tens and hundreds, means by which upon depressing a key in any series the corresponding power device will be operated to an extent determined by the key depressed, a start device for releasing the parts moved by one of the power devices, restoring means by which released parts are returned to normal position, and automatically operated means controlled by returning parts for releasing other parts so that they may also be restored to normal position.

6. In a calling mechanism, a device movable from normal position by air pressure, a series of keys arranged in a row and each key serving when depressed as means for stopping the moved device a different distance from its normal position, means for locking a depressed key in depressed position, means by which the depression of any key serves to start the device from its normal position, means for releasing the moved device, power means for returning the released device to its normal position, and means controlled by such return for releasing the depressed key.

7. In a calling mechanism, a movable body as a wheel 24, power devices for moving said body from and returning it to normal position, a series of keys each one of which serves when depressed to start one power device to move the body from normal position and to arrest such movement at a different point, locking mechanism for holding a depressed key in depressed position, manually operated means for causing the other power device to return the moved body to normal position, electrical contacts operated

by such return movement, and means by which the completion of the return movement releases the locking mechanism.

8. In a calling mechanism, a series of keys for the digits in units, a second series of keys for the digits in tens, means by which upon a key being depressed it will be locked in depressed position and the other keys in the same series will be locked against depression, an independent power device for each series of keys, a contact operating device associated with each power device, means by which upon depressing one key in each series the mechanism will be set for calling a number corresponding to the keys depressed, a manually operated start device, and automatically operating means by which upon operating said start device the contact operating devices will be operated a number 20 of times which corresponds to the number for which the mechanism was previously set.

9. In a calling mechanism, a separate series of keys for the digits in units, in tens, in hundreds and thousands; a separate locking device for each series arranged to prevent the depression of more than one key in a series; separate power mechanism for each series of keys; a contact making device; and means by which upon starting one power 30 mechanism into operation the others will follow automatically in succession and will operate the contact making device the number of times indicated by previous depressed keys in the different series of keys.

35 10. In a calling mechanism, a series of cylinders each having a piston and connections by which the piston is moved in the

cylinder, a series of numbered keys associated with each cylinder, means by which upon depressing any key the corresponding piston will be moved automatically a distance represented by the number on the depressed key, a contact making device operable by movement of each piston a start device arranged to be operated after one key in each series has been depressed, and means by which upon operating said start device the pistons will automatically return in succession to their original positions and in so returning will operate the contact making device the number of times indicated by the depressed keys.

11. In a calling device, a movable tape or belt having a stop secured thereon, a series of keys each of which is movable to a position in the path of said stop, means by which upon depressing a key the tape will be started to move and will be arrested by the stop engaging the depressed key, automatic means for returning the stop to its original 60 position, and a contact making device operated by such return movement.

12. In a calling device, a cylinder and piston, a valve for admitting air to the cylinder to move the piston, a series of keys each one of which when depressed serves to operate said valve, means associated with the keys for stopping the movement of the piston at a different position for each key, separate means for reversing the valve so as to permit the piston to return to normal 65 position, and a contact making device operated by such return movement.

FRANK A. LUNDQUIST.
